AUTOMOTIVE SIGNAL HOUSING

Sidney A. Heenan, Park Ridge, Anthony J. Montalbano, Des Plaines, and Norbert Majewski, Elk Grove Village, Ill., assignors to Amerace Esna Corporation, New York, N.Y.

Filed Sept. 13, 1972, Ser. No. 288,641

Term of patent 14 years

Int. Cl. D26—06

U.S. Cl. D48—32 R

FIG. 1 is a perspective view of an automotive signal housing incorporating our new design;

FIG. 2 is a top plan view of the automotive signal housing;

FIG. 3 is a front elevational view of the automotive signal housing;

FIG. 4 is a rear elevational view of the automotive signal housing; and

FIG. 5 is a side elevational view of the automotive signal housing.

We claim:

The ornamental design for an automotive signal housing, substantially as shown.
